METHOD OF MAKING CAR COUPLER YOKES

John B. Tegarty, St. Clair, Mich.

Original application February 23, 1935, Serial No. 7,687. Divided and this application May 10, 1937, Serial No. 141,662

2 Claims. (Cl. 29—167)

This invention relates to an improved method of making yokes for railway car couplers, and is a division from my co-pending application, Serial No. 7,687, filed February 23, 1935, now Patent Number 2,149,640, granted March 7, 1939.

The preferred embodiment of the invention discloses a yoke comprising a number of simple parts rigidly welded together to provide a strong unitary structure.

10 In the above identified application, prior methods of making yokes are discussed and the disadvantages of these methods clearly set forth. The principal disadvantage of these prior yokes is that the head portion, which attaches to the 15 shank of the coupler, is a one-piece forging or casting usually riveted to the body of the yoke member. The severe shocks to which these yokes are subjected cause loosening of the rivets, necessitating frequent replacement or at least a 20 thorough examination of this portion of each railway car.

The principal object of the present invention, therefore, lies in the provision of an improved method of manufacturing car coupler yokes which is far less expensive than the prior yokes 25 now in common use.

Another object is to simplify the method of making such car coupler yokes so that they are better adapted to withstand the severe abuse and 30 at the same time provide a simple construction requiring only a few simple parts which are welded together as a unit and comprise the yoke.

Other objects and advantages will become apparent from consideration of the following specification and accompanying drawing, in which:

Fig. 1 shows a fragmentary perspective view of a coupler yoke as viewed from the upper portion thereof; and

Fig. 2 is a fragmentary perspective view of the 40 coupler shown in Fig. 1, looking from the lower side thereof.

Referring to Figs. 1 and 2, the yoke is shown comprising a heavy flat strip of steel or wrought iron bent substantially midway of its extreme 45 ends in the form of a U to provide a pair of vertically spaced substantially parallel arms 1 and 2 which extend forwardly from an integral transverse portion 3. The portion 3, being at the rear of the yoke and providing the abutment 50 which reacts against the car frame during use, may be suitably reinforced by welding a plate 4 in juxtaposition with the inner face of the portion 3, as shown in Fig. 1.

The forward ends of each of the arms 1 and 2 55 are offset slightly toward each other so that

extreme end portions 5 and 6, respectively, extend in a direction substantially parallel to the major portions of the arms 1 and 2. Thus the vertical space between the end portions 5 and 6 is less than the space between the main portion 5 of the arms 1 and 2.

Interposed between the end portions 5 and 6 and securely welded to the inward faces thereof is a block 8 which is preferably a metal casting or a forging. The block 8 is provided with a 10 plurality of vertically spaced forwardly extending tongues 10. These tongues extend in a direction parallel to the end portions 5 and 6 and are preferably substantially the same shape as the said end portions. In the present instance, 15 these end portions 5 and 6 and tongues 10 are semi-circular in shape to permit a free laterally swinging movement of the coupler when it is attached to the yoke. Thus, when the block 8 is in assembled position, the semicircular ends of 20 the portions 5 and 6 provide additional tongues similar to tongues 10. All of these tongues are vertically spaced and substantially parallel, as shown in Figs. 1 and 2. The space between adjacent tongues is capable of receiving suitable 25 tongues or protuberances on the shank portion of the car coupler. The end portions 5 and 6 and tongues 10 are provided with aligned openings 12 for receiving a suitable draw pin which, when 30 installed in position, passes through similar openings in the shank portion of the coupler for securing the said coupler to the yoke.

On the lower face of the end portion 6 is a finger 13 which is provided with a horizontally and forwardly extending portion disposed in vertical alignment with the openings 12 so that the draft pin, when in assembled position, rests with its lower end on the horizontal portion of the finger 13 so as to limit the downward position of the pin. On the upper face of the end portion 5 is a pair of blocks 15, each block being disposed in laterally opposite sides of the opening 12 and provided with aligned openings 17 for the purpose of accommodating a retaining pin for the draft pin to prevent inadvertent removal of the draft pin during use.

From the above description, it will be seen that an improved method of making car coupler yokes has been described, which is consistent with the objects set forth.

Although but one form of the present invention has been shown and described, it will be apparent to those skilled in the art that other forms may be made without departing from the spirit and scope of the appended claims.

Having thus described my invention, what I claim is:

1. A method of making a car coupler yoke comprising bending an elongated metal body member of equal thickness throughout its length into a U-shape to provide forwardly directed spaced arms, bending the forward end portions of said arms into substantially parallel and in more closely spaced relation than the remaining portion of said arms, welding between the more closely spaced end portions of said arms a rigid head member so that its entire end surfaces are in juxtaposition with the inner parallel faces of said closely spaced arm portions, and providing aligned openings through the forward end portions of the arms and the head member.

2. A car coupler yoke comprising a strip of rolled steel of the same cross section substantially throughout its length and in the form of a U with forwardly extending spaced arms, the forward end portions of said arms being offset relatively toward each other from the planes of the remainder of the arms and with flat inner faces substantially parallel with each other, a rigid head member disposed between said offset portions with its ends abutting the opposed parallel flat faces thereof and rigidly welded thereto over the entire areas of said ends, the forward end portions of said arms and said head member having aligned openings for receiving a coupling member.

JOHN B. TEGARTY.
